FURRING STRIP

William Huber, Jr., Glendale, Calif.

Application July 11, 1947, Serial No. 760,259

3 Claims. (Cl. 72—118)

1

This invention relates to furring strips more particularly adapted for stucco-covered walls.

An object of the present invention is to provide new and improved means whereby uniformity of application of stucco or similar material to a wall may be obtained without the need for great skill on the part of the plasterer.

Another object of the invention is to provide a novel and improved furring strip for use in supporting one or more layers of wire mesh to prepare a wall for receiving stucco.

Another object of the invention is to provide wire mesh support furring for the ultimate provision of a stucco-covered wall that resists weave and shock and is fireproof to a high degree.

The over-all strength of a stucco wall is related to the uniformity of application of the scratch and finishing coats. An uneven primary or scratch coat will result in a wall having strong tendencies to crack and to yield, at its weaker parts, to shock, etc. This invention, therefore, seeks to provide simple means, readily usable by apprentices and other relatively unskilled helpers, for preparing a wall to receive uniform layers of scratch and finish coats of stucco.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a broken view, as seen from the outer face of a wall, showing the manner of application of the invention in various stages through the wall thickness.

Fig. 2 is an enlarged cross-sectional view as taken on the line 2—2 of Fig. 1.

Fig. 3 is a broken side view of a furring strip shown in Figs. 1 and 2.

Fig. 4 is a broken pattern view of said furring strip.

The wall, upon which the instrumentalities of the invention are applied, may be variously constructed. As shown, said wall comprises wooden studs 5 covered on their outer faces by tar paper sheeting 6 or the like.

2

According to the invention, the wall has applied thereon a plurality of furring strips 7 of novel form to support a wire mesh 8 in proper spaced relation to the sheeting 6 and for the purpose of reinforcing and guiding the uniform application of a base or scratch coat or layer of stucco or like material 9, and a plurality of furring blocks 10 mounted on said furring strips to mount and space a second wire mesh 11 from the first wire mesh for the purpose of reinforcing and guiding the uniform application of a second or finishing coating or layer 11a of stucco or like material.

The furring strip which is shown in the drawing, and with more particular reference to Fig. 4, comprises, generally, an integral light-gauge metal strip formed with spaced longitudinal and parallel portions 12 and longitudinally spaced connecting portions 13. Said strip, along fold lines 14 and 15, is adapted to be formed or bent, as in Figs. 2 and 3 to provide a saddle 16 having the shape of an inverted U.

Between each pair of fold lines 14 and 15 there is defined a side wall 17 having edges each formed with a notch 18, and between fold lines 15 there is defined a top plate 19. The connecting portion 13 is further formed with tabs 20 as longitudinal extensions of the top plate 19 and said tabs are normally angularly and downwardly directed as indicated in dot-dash lines in Fig. 3, being bent on a fold line 21.

Each of the longitudinal portions 12 is provided with a plurality of spaced holes 22 for nails 23 employed to fasten the strip 7 in place. Another and optional means of fastening said strip, as shown in Fig. 1, comprises a large-headed nail 24 arranged to catch adjacent edges of said portions 12 substantially as shown. The walls 17 are also preferably provided with holes 25 and the top plate 19 with a hole 26.

In practice, the strips 7, arranged in any suitable direction, are secured in place by nails 23 and/or nails 24 and the wire mesh 8 is mounted in spaced relation to the sheeting 6 by catching portions of said mesh in one notch 18 of each or most of the saddles 16, as seen in Fig. 3, and then bending the tabs 20 inward so that they serve as clinchers for the mesh and also form closures for the interior of the saddle. The primary or scratch stucco layer 9 is now applied to an approximate thickness indicated by line 27 of Fig. 2, the closure tabs 20 keeping stucco from filling in the interiors of the saddles.

At a suitable time thereafter and when said scratch layer has dried, the furring blocks 10 are mounted on as many of the saddles 16 as is

thought necessary. Each block may be cylindrical, as shown, or otherwise shaped and may advantageously be made of non-combustible composition material. The blocks are simply nailed in place by suitably long nails 28 entering through holes 26 and, in the process of nailing, the second mesh 11 is caught under the heads of said nails and thereby held in spaced relation to the scratch layer by said furring blocks. Should the holes 26 become clogged during application of the scratch layer, the nails 28 will readily dislodge such pieces of stucco to fall into the interior areas defined by the saddle walls and the tabs 20. Since said interior areas are substantially free of stucco, the nails 28 meet no obstructions when being applied.

In the above manner there is provided a second outer mesh, uniformly spaced from the already embedded inner mesh, to serve as a guide for the uniform application of a second coat or layer or an outer or finish coat 11a, as desired. The line 29 of Fig. 2 suggests the outer surface of such a layer.

While it is preferred to provide the furring strips as described, it will be evident that separate individual saddles may be applied for effecting the spaced mounting relationship of the wire meshes.

The holes 25 may be optionally employed for wire clips inter-connecting with the wire mesh 8 to mount the same. In this disclosure and in the appended claims, the term "wire mesh" is intended to include reinforcing fabrics generally, examples thereof being chicken wire, expanded metal, and various types of metal fabrics.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In a wall structure, a vertical stud, a furring strip formed of sheet metal and having longitudinally extending side strips and saddles spaced from each other longitudinally of the side strips, said side strips being formed with openings, nails passing through said openings into the stud to secure the strips against the stud, said saddles each having a flat bridge and side walls extending from opposite side edges thereof and integrally united with the inner side edges of the side strips, the side walls of the saddles having end edges formed with V-shaped recesses and the bridge having end portions projecting beyond the side walls and constituting tongues, a first layer of wire mesh having portions fitting about said saddles and engaged in said recesses, said tongues being bent inwardly between the side walls and serving to hold the

wire mesh in the recesses and constituting mortar-excluding barriers for the ends of the saddles, blocks disposed against the bridge portions of certain of said saddles and formed with openings registering with the openings in the bridges, a second layer of wire mesh having portions thereon bearing against said blocks, and nails passing through the registering openings of the blocks and the saddles and into the stud, the heads of the nails overlapping and gripping the last mentioned wire mesh to hold the same against the blocks.

2. A metal furring strip comprising longitudinally extending side strips spaced transversely from each other, saddles spaced from each other longitudinally of the side strips, each saddle having a bridge and side walls extending from the opposite side edges thereof and integrally united with the inner side edges of the side strips, said side walls having end edges formed with recesses constituting seats adapted to receive portions of a sheet of wire mesh, the bridges at each saddle having end portions extending beyond the side walls and forming tongues bent downwardly and inwardly between the side walls and extending in crossing relation to the inner ends of the recesses in position adapting them to extend across the said portions of the wire mesh and secure the same in the recesses, said tongues being of a length and width adapting them to fit snugly between the side walls and thereby constitute mortar-excluding barriers for the ends of the saddles.

3. A furring strip comprising longitudinally extending side strips spaced transversely from each other, saddles between the side strips spaced from each other longitudinally thereof, each saddle having a bridge and side walls extending from the opposite edges thereof and connected with the side strips, said saddles being open at their ends, and tongues at the ends of the bridge of each saddle extending inwardly between the side walls thereof and constituting mortar-excluding barriers for the saddle, said side walls having recesses at their ends, said tongues extending downwardly in crossing relation to the inner ends of the recesses in position adapting them to extend across and secure portions of a sheet of wire mesh in the recesses.
